UNITED STATES PATENT OFFICE.

HENRY F. CLARK, OF POUGHKEEPSIE, NEW YORK.

PATCHED BULLET AND METHOD OF MAKING THE SAME

SPECIFICATION forming part of Letters Patent No. 286,887, dated October 9, 1883.

Application filed April 27, 1883. (No model.)

To all whom it may concern:

Be it known that I, HENRY F. CLARK, of Poughkeepsie, in the county of Dutchess and State of New York, have invented a certain 5 new and useful Improvement in Patched Bullets and in the Manufacture of Patched Bullets, of which the following is a specification.

This improvement consists in the combination, with a bullet having a conoidal portion 10 at the forward end and a cylindric portion at the rear end larger in diameter than said conoidal portion, thereby forming a shoulder at the junction of the cylindric portion and the conoidal portion, of a patch applied to the cylindric portion and extending over said shoulder.

The improvement also includes a novel method of patching a bullet, consisting in first forming a tubular patch, open at both ends, by coiling paper cylindrically and fastening the outer end to the adjacent coil, the patch being sufficiently larger than the slug from which the bullet is formed to enable it to be readily slipped over the end of the slug and upon the cylindric portion thereof, and in subsequently expanding the slug, by pressure exerted in the direction of its length, to complete its formation into a bullet, and to cause it to tightly fill the interior of the tubular patch, so that the latter will be retained in place thereon.

In the accompanying drawings, Figure 1 is a side view of a slug. Fig. 2 is a side view of a patch. Fig. 3 is a longitudinal section of the bullet with the patch in place. Fig. 4 is 35 a face view of a strip of paper suitable for use in making patches like the one shown in other figures, and Fig. 5 is a side view of a tube formed from such a strip. All these views illustrate the devices upon an enlarged scale.

40 Similar letters of reference designate corresponding parts in all the figures.

A designates the bullet, and B designates the patch. The bullet consists of an approximately-cylindrical portion, *a*, and a conoidal portion, *b*, at the fore end. The slug from which the bullet is formed has the same characteristics, but is slightly smaller diametrically. The patch is made by taking a strip of paper (shown in Fig. 4) as wide as the length of several of the patches to be produced, and winding it

upon a stick or other mandrel, so as to produce a long tube (shown in Fig. 5) slightly larger internally than the external measurement of the slugs upon which it is to be used. Preferably the outer coil of the strip of paper will 55 be externally lubricated after being wound to form a tube and subsequently to having the outer end fastened. The ends of the strip may be united to the next adjacent coils by mucilage, or any other adhesive substance; or its outer end only may be thus fastened. This tube is cut into pieces of lengths suitable for patches. The patches are preferably slipped over the slugs while the latter stand on their rear ends upon a flat surface, and are pushed 60 down to said surface to arrange them so that their rear edges will be even with the rear ends of the slugs. The slugs are swaged or upset in suitable dies, so as to complete their formation into bullets and expand them tightly into 65 patches. The patches are a trifle longer than the cylindrical rear portions of the bullets; hence they extend slightly over the shoulders, which are formed at the junction of the cylindrical rear portions and the conoidal 70 fore portions, and they preferably extend slightly over the shoulders or corners at the rear ends. The patches thus made are applied to the slugs in a dry state; and though they are more firmly secured in place when the slugs 75 are expanded into them, they are nevertheless more easily freed therefrom by the rifling of the fire-arm in which they are used, for a single longitudinal cut by the rifling through the outer coil of the patch will loosen and free the 80 coils of the paper, thus allowing them to escape, because the coils do not adhere together. The extension of the patches over the shoulders of the bullets prevents the metal of the shoulders from coming in contact with the 85 rifling of the fire-arm. A patch extended over 90 a shoulder on a bullet is preferable to one extending over a tapering portion of a bullet, for the portion of the patch extending over the tapering portion of a bullet will be so loose 95 that it will yield when brought in contact with the rifling, and, not being cut, will be apt to remain attached. When the bullet, by a pressure exerted in the direction of its length, is expanded into its patch, it is unnecessary to 100

turn the patch into a hollow in the rear end of the bullet, or to twist the rear edges of the patch over the rear end of the bullet; hence the freeing of the patch from the bullet may be effected with greater facility, and the rear end of the bullet can be made of any desired shape.

Bullets patched according to my improvement may be used in fixed ammunition as well as in other ammunition. When used in fixed ammunition, they may be merely seated in the shells.

What I claim as my invention, and desire to secure by Letters Patent, is—

1. The combination, with a bullet having a conoidal portion at the fore end and a cylindric portion at the rear end larger in diameter than the conoidal portion, thereby forming a shoulder at the junction of the cylindric portion and the conoidal portion, of a patch applied to the cylindric portion and extending over said shoulder, substantially as specified.

2. The method of patching a bullet herein described, consisting in first forming a tubular patch, open at both ends, by coiling paper cylindrically and fastening the outer end to the adjacent coil, the patch being sufficiently larger than the slug from which the bullet is formed to enable it to be readily slipped over the end of the slug and upon the cylindric portion thereof, and in subsequently expanding the slug by pressure exerted in the direction of its length, to complete its formation into a bullet, and to cause it to tightly fill the interior of the tubular patch, so that the latter will be retained in place thereon, substantially as here- in specified.

H. F. CLARK.
